UNITED STATES PATENT OFFICE.

ABRAHAM WOOD AND GRANVILLE WOOD, OF STUBBINS, NEAR MANCHESTER,
ENGLAND.

ELECTRICALLY-CONTROLLED CLOTH GUIDER AND THE LIKE.

Application filed August 12, 1924, Serial No. 731,642, and in Great Britain and Ireland August 17, 1923.

This invention refers to electrically-controlled cloth guiders and the like wherein electro-magnets are used to control guiding rollers, and wherein are "feeler" levers which are acted upon by the selvedges of the cloth and which in turn control the circuits of the magnets. The main object of this invention is to provide a new or improved circuit breaker or controller with each electro-magnet which will be better adapted for rapid and constant making and breaking (or controlling) of the circuit, and will not require the same attention, or to be renewed so frequently, as the ordinary metal-to-metal spring-pressed type of circuit breaker or controller. A further object is to provide an improved arrangement of electrically-controlled guiders as an attachment to, or an integral part of the machine with which they require to be used, instead of being embodied in a separate machine. Another object is to provide a construction of electrically-controlled guiders attached to or forming part of the machine and adapted to guide two or more widths of cloth simultaneously.

The foregoing objects of the invention, together with means whereby the same may be carried into effect, will best be understood from the following description of two forms or embodiments thereof illustrated in the accompanying drawings.

In said drawings:

Fig. 1 illustrates a front elevation, and

Fig. 2 a plan view of the improved cloth guider according to one example of the invention.

Fig. 3 is a plan view of a further example of the invention, while

Figs. 4 and 5 illustrate cross sections of part of the guider as shown in Figs. 1 and 3 respectively drawn to a larger scale.

Fig. 6 illustrates a rear elevation, and

Figs. 7 and 8 a left and right hand view respectively drawn to a larger scale, of one of the roller and magnet units of the improved machine.

Fig. 9 illustrates an enlarged sectional elevation of the electrical make-and-break mechanism used with the improved roller and magnet units.

Fig. 10 illustrates an enlarged sectional elevation of a modification hereinafter described.

In carrying out the first part of the invention and as shown in Figs. 6 to 9 two

carbons *a*, *b*, are employed. The carbon *a* is round in shape, and the other carbon *b* is elongated or substantially rectangular in shape two of its longer sides being slightly concave. The round carbon *a* is mounted on a pin *a*¹ extending from a fixed metal plate *a*² secured to an insulating block *c*, and the elongated carbon *b* is mounted on a plate-like lever *d* pivoted at its lower end to the feeler lever *e*. The metal plate *a*² is formed with a tongue or spur *a*³ with curved extremity, see Fig. 9, and lying in the plane of the lever *d* carrying the elongated carbon *b*, the normal position of the parts being with the two carbons in contact, i. e. one resting upon or against the other, in which position they complete the circuit of the adjacent electromagnet. On the feeler lever *e* moving towards the insulating block *c* the elongated carbon *b* first slides upon the round carbon *a* and then rapidly moves away from same in the arc of a circle, this latter movement being brought about by the lever *d*, carrying the elongated carbon, meeting the end of the metal tongue or spur *a*³ which tilts the lever about its pivot *d*¹ on the feeler lever and thereby rapidly breaks the contact between the two carbons. On the feeler lever *e* moving in a direction away from the insulating block *c*, the elongated carbon *b* is first quickly lowered by gravity into contact with the round carbon *a* and then caused to slide thereon before coming to rest. The lever *d* may be of vulcanite or like insulating material and the carbon *b* may lie against a facing of sheet copper *d*² which will extend to a screw terminal *d*³ on the lever, connected by a flexible conducting wire *d*⁴ to a fixed terminal *c*¹ on the insulating block *c*.

The insulating block *c* is provided with the terminals *c*², *c*³, *c*⁴, *c*⁵ for the leads to and from the electro-magnets, the carbon holders, the main or source of current, and "earth" return.

The carbons may partake of other shapes but by making one round and the other elongated they allow of prolonged use, the round block merely requiring to be given a slight rotation periodically when showing signs of wear, and the elongated block allowing of being reversed when worn on one side and of its four sides being brought to bear successively on the round block. The use of carbon contacts and particularly

electrographite carbon contacts is found highly satisfactory in practice, and enables a current of high voltage to be used direct from a power main.

5 In the end brackets n , n , see Figs. 1, 2 and 3 are arranged the electrical terminal blocks to which the leads from the main are connected, and the leads to the guide roller magnets, the latter being connected in 10 parallel.

In Fig. 1, the terminal block in the left hand bracket is connected by a three-wire cable o to the terminal block in the right hand bracket, and combined with one of the 15 terminal blocks is a common switch p controlling the magnets of both pairs of guide rollers.

From each end terminal extends the further three wire cable q , which is connected 20 to the terminals c^1 , c^2 and c^3 of the insulating block c of the contact breaker, see Fig. 9.

In carrying out the further features of the invention, the said improved electric controlling mechanism is housed in a metal box 25 f provided on its rear side with metal straps or loops f^1 , f^2 by which it is slidably mounted on a metal bar g^1 extending across the machine.

In one with the metal box is formed a 30 guide plate h^1 and detachably secured to said box is a further guide plate h^2 the two plates lying at a slight distance apart to allow the cloth to be guided to pass between. With said box is pivotally mounted the 35 feeler lever e which at its lower end has a pin or stud e^1 which extends horizontally across the space between said guide plates, these latter being formed with slots h^3 .

In a recess cast in one end of the box f 40 is an electromagnet i , the poles of which lie flush with or project slightly beyond the outer face of the casting and mounted upon the free end of one of the radius arms j , hinged to the guide plate h^2 and carrying 45 one of the guide rollers k^1 is a soft-iron keeper or armature l . In fixed bearings m on the guide plate h^1 is the companion guide roller k^2 the rollers lying parallel and their axes being inclined to the horizontal, see 50 Fig. 6. The carrier bar g extends from end bracket n to end bracket n or from side frame to side frame of the machine with which the guiders are to be used. Or, when 55 not desired, or when not practicable to make the apparatus integral with the machine, the said bar is mounted in separate brackets arranged in front of the machine.

For guiding a single width of cloth there 60 will be two pairs of guide rollers k^1 , k^2 , one for one edge of the cloth and the other for the other edge, each pair being separately controlled. When two or more widths of cloth require to be guided at once, two carrier bars g , g may be provided and one bar 65 arranged to the rear of and slightly higher

than the other, and each bar having its guide roll arranged below it, see Figs. 3 and 5. Upon one bar are two pairs of guide rollers and upon the other bar one pair, each pair being electrically controlled and each adjustable along the bar to suit the width of cloth to be guided. In the case of narrow cloth, two or more widths of cloth may be guided by one bar, two or more sets of guide rollers being on said bar. 75

In Fig. 10 the electrical contact breaker is arranged to operate with the feeler lever pin e above, instead of below the contact breaker. In this case the required rapid breaking movement is obtained by means of the fixed pin a^1 against which the carbon, carrying lever d bears on the feeler lever moving it towards the block c , the lever being pivoted and proportioned so as to cause the feeler lever pin a^1 normally to bear 85 against the end of its cloth.

The carbon blocks a , b will preferably be detachably secured on their respective supporting studs or pins a^1 and b^1 by means of forked spring key members engaging 90 grooves in the pins and flush with the carbons.

In the block b are small holes, one of which engages a pin on the lever e to prevent 95 accidental displacement of the carbon.

What we claim is:—

1. In electrically-controlled cloth guiders, a pair of end brackets, at least one cross-bar connecting said end brackets, pairs of boxes 100 slidably mounted on said cross-bar, a pair of inclined guide rollers carried by each box, one roller being movable towards and away from the other, a pair of guide plates on each box, and a "feeler" lever for each pair of plates and rollers, an electro-magnet housed in each box, said magnets being connected in parallel, a circuit breaker also housed within each box, said circuit breaker comprising a pair of contact blocks one of which is relatively stationary while the other is capable of being moved bodily first in sliding contact with the stationary block and then rapidly away from said block, and vice versa, as set forth. 110

2. In electrically-controlled cloth guiders, a pair of end brackets, at least one cross-bar connecting said end brackets, pairs of boxes 115 slidably mounted on said cross-bar, a pair of inclined guide rollers carried by each box, one roller being movable towards and away from the other, a pair of guide plates on each box, and a "feeler" lever for each pair of plates and rollers, an electro-magnet housed in each box, said magnets being connected in parallel, a circuit breaker also housed within each box, said circuit breaker 120 comprising a round stationary carbon block, and an elongated movable carbon block, means for pivotally supporting the movable carbon block on the feeler lever, the said 125 130

blocks or their carriers being insulated from their supports and being electrically connected to the terminals of the electro-magnets, and to the main, and means whereby the movable carbon, after sliding over the stationary carbon, is caused to move rapidly away in the arc of a circle, as set forth.

3. In electrically-controlled cloth guiders, guider units comprising a metal box with slotted lugs to allow it to slidably fit a cross-bar, bearings for the axis of a roller in one with said box, and a guide roller on said axis, a further roller and axis therefor, levers pivoted to the box for carrying said further roller axis, the axes of the two rollers being inclined, guide plates with slots and lying a slight distance apart, secured to the box, a pivoted "feeler" lever within the box having a cross pin which projects through the slots and across the space between

the guide plates, an electro-magnet housed in the box and a circuit breaker also housed in said box, the circuit breaker comprising a pair of contact blocks, one stationary and the other movable, a relatively stationary 25 plate with cam-shaped edge carrying the stationary contact block, a lever made of insulating material carrying the movable block, said lever being pivoted on the said feeler lever, and lying in the plane of the 30 plate with cam-shaped edge, and opposite such edge, and on the feeler lever being moved to break the circuit of the electro-magnet, first sliding the movable contact block over the stationary block and then 35 quickly separating the blocks, as set forth.

In testimony whereof we have signed our names to this specification.

ABRAHAM WOOD.
GRANVILLE WOOD.
